TREATMENT OF POLYMERIZABLE PETROLEUM DISTILLATES

William T. Hancock, Long Beach, Calif.

Application January 22, 1940, Serial No. 315,010

13 Claims. (Cl. 196—147)

This invention relates generally to the treatment of polymerizable petroleum hydrocarbons by the action of adsorptive material, and is particularly concerned with improvements in processes of the general type disclosed in Patent Number 2,162,715 issued to me June 20, 1939 on Process for refining cracked petroleum distillate.

In accordance with the method employed in the patented as well as present processes, heated pressure distillate is subjected to polymerization by intimately contacting it with a suitable adsorptive material such as fuller's earth, bentonite, Muroc or Death Valley type clays, and the polymerized distillate then is mixed with a heated heavier oil having a higher boiling range than the gasoline content of the pressure distillate. Gum-forming and sulphur-containing impurities are removed from the polymerized gasoline by vaporizing the latter, leaving such impurities in the unvaporized higher boiling oil. The vapors may then be treated or fractionally condensed by any suitable method to produce the final gasoline product.

The process described in the patent referred to above contemplates mixing the polymerized distillate and heated higher boiling oil under pressure in a flow line or mixing chamber, and then flash-vaporizing at least a portion of the gasoline content of the distillate by discharging the mixed oils into a vaporizing zone maintained under reduced pressure. According to certain aspects of the present process, the polymerized distillate is delivered, with or without pressure reduction, into an enlarged mixing zone and therein contacted with the heated higher boiling oil and subjected to vaporization by the heat contained in that oil. Preferably the vaporized distillate is caused to flow upwardly in intimate contact with the higher boiling solvent oil in the mixing zone, as by maintaining a continuous downward circulation of the solvent oil in the path of the rising vapors. Heat is supplied to the solvent oil by continuously circulating the oil between the mixing chamber and an external heat source, such as a tubular heater.

The invention further contemplates, when necessary or desirable, subjecting the hydrocarbons vaporized from the higher boiling oil, as described, to second stage polymerization and treatment with heavier oil. The initially polymerized hydrocarbons may be passed, either in liquid or vapor phase, through a second polymerizing zone containing adsorptive material, then admixed with heated higher boiling oil in a second mixing zone, and finally subjected to fractionation or condensation.

A more complete understanding of various features and objects of the invention, as well as the operation of a typical and illustrative system embodying the invention, will be had from the following detailed description, throughout which reference is had to the accompanying drawing showing such typical system diagrammatically and in flow sheet form.

The polymerizable hydrocarbon to be treated, for example, pressure distillate having an end point of about 425° F., is introduced to the system through line 10. Where the distillate is not preheated to proper polymerizing temperature, the distillate may be passed through heater 11 and therein heated to a temperature of at least 200° F. and preferably higher, to around 325° F. to 350° F. When otherwise preheated, the distillate may be discharged from line 10 through line 12 for treatment in the first polymerizing zone. The heated pressure distillate is introduced through line 13 to a heat-insulated polymerizing chamber 14 containing a body 15 of adsorptive material of the character above mentioned, the distillate flowing vertically through the chamber in direct and intimate contact with the adsorptive material, and thus undergoing polymerization to convert its gum-forming and a large percentage of sulphur-containing compounds, to polymerized condition. The pressure distillate stream, containing the polymerized compounds, is discharged from the polymerizing zone through line 16 and is introduced into the lower portion of a heat insulated contactor generally indicated at 17. The distillate may flow from the polymerizing zone to the contactor either with or without pressure reduction, as may be controlled by valve 18, it generally being preferred to maintain sufficient pressure on the distillate during polymerization that at least the major portion of the distillate will remain in liquid phase at the temperature to which the distillate is preheated. Ordinarily the heat transmitted from the higher boiling solvent oil, as later described, will be sufficient to vaporize the gasoline fractions in the pressure distillate at the polymerizing pressure, although wherever desired, vaporization of the gasoline fractions may be facilitated by some pressure reduction at the valve 18.

The polymerized distillate stream flows from line 16 into a body 19 of higher boiling oil, for example gas oil, fuel oil or a crude oil with or without gasoline content, maintained within the lower mixing chamber 17a of the contactor 17. If desired, the higher boiling oil may be maintained at a minimum level L within the mixing chamber

by suitable means such as a liquid level control, diagrammatically indicated at 20, having an operating connection 21 with a valve 22 in the outlet line 23. The higher boiling oil is taken from a suitable source, such as an accumulator 24, through line 25 to a heater 26 wherein the oil is heated to a temperature sufficiently high to effect vaporization of the gasoline fractions in the pressure distillate. This temperature ordinarily will be in excess of 300° F. and preferably in the neighborhood of from 500° F. to 600° F. Leaving the heater 26, the higher boiling oil enters the mixing chamber of the contactor through line 27. Thus a continuous circulation of the higher boiling oil is maintained between the heater and mixing chamber, the circulation being conducted through accumulator 24 in order to stabilize the flow and to permit removal of gums and other impurities left from the pressure distillate in the heavier oil, through line 28. The flow through line 28 may be substantially continuous, under control of a regulator 29 that maintains a liquid level in the accumulator, and the system is thus continuously freed of a portion of the gums and impurities carried in and settling to the bottom of the heavy oil, as well as any excess of heavy oil resulting from the accumulation of higher boiling and unvaporized ends of the pressure distillate. Make-up solvent oil may be fed to the system through line 30 at sufficient rate to prevent, by dilution of the oil being circulated, excessive accumulations of gums and polymers.

If desired, the mixing chamber 11a may contain suitable means for causing the rising pressure distillate stream to be divided and thus subjected to more intimate contact with the heavy oil, as by providing a series of screens 31 above the point of entry of the distillate. Upon being admixed with and during the course of its flow upwardly in the higher temperature solvent oil, 40 the pressure distillate becomes heated to a temperature sufficiently high to vaporize at least its gasoline content, the vapors as they are formed passing upwardly through the heavier oil to the upper interior of the contactor. The vapors may 45 be subjected to reflux condensation within a dephlegmating zone 17b, so that the heavier-than-gasoline ends are continuously condensed and returned to the body 19 of heated solvent oil. The dephlegmating zone 17b may contain a series of perforated plates or bubble trays 32, and 50 may be operated with or without reflux from an extraneous source. Preferably, however, a portion of the circulated higher boiling oil stream is introduced through line 33 to the upper interior of the dephlegmating zone for the purpose of securing a final and down-flowing contact with the rising pressure distillate vapors.

Leaving the contactor 17, the gasoline hydrocarbons are taken through line 34 to be condensed or subjected to further treatment, as may be necessary or desirable depending upon the characteristics of the pressure distillate and the completeness with which the polymerizable or sulphur containing impurities have been removed in the contactor 17. In the treatment of some distillates it may be desirable to again subject the gasoline hydrocarbons to polymerization and treatment with heated heavier oil, and for this purpose the hydrocarbons may be taken from line 34 into a second polymerizing zone 35 and passed downwardly through adsorptive material 36 as in the first described polymerizing zone. In this second stage polymerization the gasoline may be contacted with the material 36 75

in either liquid or vapor phase, although I prefer to effect the polymerization in liquid phase. For this purpose the vapors may be passed from line 34 through line 37 to a condenser 38, and the condensate, after removal of uncondensable gases through line 39, discharged by pump 40 into the polymerizing zone. After passing through the adsorptive material, the hydrocarbons flow through line 41 into the second contactor 42 wherein they are intimately contacted with a body 43 of higher boiling oil being continuously circulated from the heater 44 through line 45, and returned to the heater through line 46, accumulator 24 and lines 25 and 47. An independent heater 44 is shown to be provided for the oil being circulated through contactor 42, in order to permit the maintenance of different temperatures in the contactors, and also different circulation rates if desired.

The gasoline fractions of the pressure distillate, and perhaps some heavier ends, are admixed with the higher boiling oil in contactor 42 all as previously described, and the vapors discharged through line 48 for final fractionation and condensation. As in the first contactor, the vapors may be subjected to dephlegmation within an upper section 42a of the contactor, or treated with a down-flowing stream of the heated heavier oil introduced through line 49. As a typical method for subjecting the treated vapors to final condensation, the vapors are shown to be discharged through line 48 to a fractionating column 50 from which any heavier-than-gasoline ends are withdrawn through line 51. The vapors flow through line 52 to a final condenser 53 from which the condensate passes to a receiver 54.

As will be understood, the rate of circulation of the heated heavier oil through the mixing zone will be dependent upon the rate of pressure distillate flow and the relative temperatures of the two oils. Ordinarily the rate of solvent oil circulation will be at least two or three times that of the pressure distillate flow, and will be sufficient to provide the amount of heat necessary to vaporize the full gasoline content of the distillate. Where the pressure distillate is substantially entirely in liquid phase upon being introduced to the mixing chamber, a greater rate of heat supply by the heavier oil is required for vaporization of the distillate. If the polymerized distillate pressure be partially reduced at or in advance of the mixing chamber, the required rate of heat supply from the heavier oil may be reduced by reason of the resultant partial vaporization of the pressure distillate.

I claim:

1. The process of treating heated cracked petroleum distillate containing a gasoline fraction, that includes subjecting the distillate to polymerization by contacting it with adsorptive material in a polymerizing zone, maintaining within an enlarged mixing zone a quantity of heated oil having a considerably higher boiling range than said gasoline fraction, introducing the distillate from said polymerizing zone into the mixing zone and therein intimately comingling said higher boiling oil and the polymerized distillate at a temperature above the vaporizing temperature of said gasoline fraction at the pressure in the mixing zone, said temperature also being above the temperature of the distillate being introduced to the mixing zone, flowing the distillate upwardly through the higher boiling oil and thereby causing polymerized and sulphur-containing bodies in the distillate to become retained in the higher

boiling oil, removing the vaporized gasoline fraction from the higher boiling oil and subjecting the removed vapors to condensation, and separately removing the unvaporized higher boiling oil from said mixing zone.

2. The process of treating heated cracked petroleum distillate containing a gasoline fraction, that includes subjecting the distillate to polymerization by contacting it with adsorptive material in a polymerizing zone, maintaining within an enlarged mixing zone a body of independent heated oil having a considerably higher boiling range than said gasoline fraction, introducing the distillate from said polymerizing zone into said body of oil below the surface thereof and thereby intimately comingling said higher boiling oil and the polymerized distillate at a temperature above the vaporizing temperature of said gasoline fraction at the pressure in the mixing zone, flowing the distillate upwardly through the higher boiling oil and thereby causing polymerized and sulphur-containing bodies in the distillate to become retained in the higher boiling oil, removing the vaporized gasoline fraction from the higher boiling oil and subjecting the removed vapors to condensation, and removing the unvaporized higher boiling oil from said mixing zone.

3. The process of treating heated cracked petroleum distillate containing a gasoline fraction, that includes subjecting the distillate to polymerization by contacting it with adsorptive material in a polymerizing zone, maintaining within an enlarged mixing zone a down-flowing stream of heated oil having a considerably higher boiling range than said gasoline fraction, introducing the distillate from said polymerizing zone into said stream and thereby intimately comingling said higher boiling oil and the polymerized distillate at a temperature above the vaporizing temperature of said gasoline fraction at the pressure in the mixing zone, said temperature also being above the temperature of the distillate being introduced to the mixing zone flowing the distillate upwardly through said stream of higher boiling oil and thereby causing polymerized and sulphur-containing bodies in the distillate to become retained in the higher boiling oil, removing the vaporized gasoline fraction from the higher boiling oil and subjecting the removed vapors to condensation, and separately removing the unvaporized higher boiling oil from said mixing zone.

4. The process of treating heated cracked petroleum distillate containing a gasoline fraction, that includes subjecting the distillate to polymerization by contacting it with adsorptive material in a polymerizing zone, maintaining within an enlarged mixing zone a quantity of an independent heated oil having a considerably higher boiling range than said gasoline fraction, introducing the distillate from said polymerizing zone into the mixing zone and therein intimately comingling said higher boiling oil and the polymerized distillate at a temperature above the vaporizing temperature of said gasoline fraction at the pressure in the mixing zone, flowing the distillate upwardly through the higher boiling oil and thereby causing polymerized and sulphur-containing bodies in the distillate to become retained in the higher boiling oil, removing the vaporized gasoline fraction from the higher boiling oil and subjecting the removed vapors to condensation, passing the unvaporized higher boiling oil from said mixing zone through a heat-

ing zone, and returning the heated oil to said mixing zone.

5. The process of treating heated cracked petroleum distillate containing a gasoline fraction, that includes subjecting the distillate to polymerization by contacting it with adsorptive material in a polymerizing zone, maintaining within an enlarged mixing zone a body of an independent heated oil having a considerably higher boiling range than said gasoline fraction, introducing the distillate from said polymerizing zone into said body of oil below the surface thereof and thereby intimately comingling said higher boiling oil and the polymerized distillate at a temperature above the vaporizing temperature of said gasoline fraction at the pressure in the mixing zone, flowing the distillate upwardly through the higher boiling oil and thereby causing polymerized and sulphur-containing bodies in the distillate to become retained in the higher boiling oil, removing the vaporized gasoline fraction from the higher boiling oil and subjecting the removed vapors to condensation, passing the unvaporized higher boiling oil from said mixing zone through a heating zone, and returning the heated oil to said mixing zone.

6. The process of treating heated cracked petroleum distillate containing a gasoline fraction, that includes subjecting the distillate to polymerization by contacting it with adsorptive material in a polymerizing zone, maintaining within an enlarged mixing zone a down-flowing stream of an independent heated oil having a considerably higher boiling range than said gasoline fraction, introducing the distillate from said polymerizing zone into said stream and thereby intimately comingling said higher boiling oil and the polymerized distillate at a temperature above the vaporizing temperature of said gasoline fraction at the pressure in the mixing zone, flowing the distillate upwardly through said stream of higher boiling oil and thereby causing polymerized and sulphur-containing bodies in the distillate to become retained in the higher boiling oil, removing the vaporized gasoline fraction from the higher boiling oil and subjecting the removed vapors to condensation, passing the unvaporized higher boiling oil from said mixing zone through a heating zone, and returning the heated oil to said mixing zone.

7. The process of treating cracked petroleum distillate that includes, subjecting heated cracked distillate containing a gasoline fraction to polymerization by passing the distillate through a body of adsorptive material, heating within a heating zone an oil having a considerably higher boiling range than said gasoline fraction, mixing said distillate after passage through said adsorptive material and while heated, with a substantially large quantity of the heated heavier oil, vaporizing said gasoline fraction from the heavier oil in a vaporizing zone, leaving polymerized and sulphur-containing constituents of the distillate in the heavier oil, condensing the vaporized gasoline fraction, passing the unvaporized heavier oil from said vaporizing zone through said heating zone, and then mixing the resulting heated oil with the polymerized distillate to again use the heated oil to remove polymerized and sulphur-containing constituents of the distillate.

8. The process of treating cracked petroleum distillate that includes, subjecting heated cracked distillate containing a gasoline fraction to polymerization by passing the distillate through a body of adsorptive material, heating within a

heating zone an oil having a considerably higher boiling range than said gasoline fraction, mixing said distillate after passage through said adsorptive material and while heated, with a substantially large quantity of the heated heavier oil, vaporizing said gasoline fraction from the heavier oil in a vaporizing zone, leaving polymerized and sulphur-containing constituents of the distillate in the heavier oil, condensing the vaporized gasoline fraction, passing the unvaporized heavier oil from said vaporizing zone through an enlarged accumulator zone and through said heating zone, and then mixing the resulting heated oil with the polymerized distillate to again use the heated oil to remove polymerized and sulphur-containing constituents of the distillate.

9. The process of treating cracked petroleum distillate that includes, subjecting heated cracked distillate containing a gasoline fraction to polymerization by passing the distillate through a body of adsorptive material, heating within a heating zone an oil having a considerably higher boiling range than said gasoline fraction, mixing said distillate after passage through said adsorptive material and while heated, with a substantially large quantity of the heated heavier oil, vaporizing said gasoline fraction from the heavier oil in a vaporizing zone, leaving polymerized and sulphur-containing constituents of the distillate in the heavier oil, condensing the vaporized gasoline fraction, removing from the unvaporized heavier oil impurities retained therein from the distillate, passing the heavier oil through said heating zone, and mixing the resulting heated oil with the polymerized distillate to again use the heated oil to remove polymerized and sulphur-containing constituents of the distillate.

10. The process of treating cracked petroleum distillate that includes, subjecting heated cracked distillate containing a gasoline fraction to polymerization by passing the distillate through a body of adsorptive material, heating within a heating zone an oil having a considerably higher boiling range than said gasoline fraction, mixing said distillate after passage through said adsorptive material and while heated, with a substantially large quantity of the heated heavier oil, vaporizing said gasoline fraction from the heavier oil in a vaporizing zone, leaving polymerized and sulphur-containing constituents of the distillate in the heavier oil, condensing the vaporized gasoline fraction, removing the unvaporized heavier oil from said vaporizing zone, adding fresh oil to the heavier oil, passing the removed heavier oil through said heating zone, and then mixing the resulting heated oil with the polymerized distillate to again use the heated oil to remove polymerized and sulphur-containing constituents of the distillate.

11. The process of treating cracked petroleum distillate that includes, subjecting heated cracked

distillate containing a gasoline fraction to polymerization by passing the distillate through a body of adsorptive material, continuously heating an oil having a considerably higher boiling range than said gasoline fraction, mixing said distillate after passage through said adsorptive material and while heated, with a substantially large quantity of the heated heavier oil, vaporizing said gasoline fraction from the heavier oil in a vaporizing zone, leaving polymerized and sulphur-containing constituents of the distillate in the heavier oil, condensing the vaporized gasoline fraction, and removing from said vaporizing zone and again mixing with the polymerized distillate a continuously circulated stream of said heavier oil to again use the heated oil to remove polymerized and sulphur-containing constituents of the distillate.

12. The process of treating cracked petroleum distillate that includes, subjecting heated cracked distillate containing a gasoline fraction to polymerization by passing the distillate through a body of adsorptive material, continuously heating an oil having a considerably higher boiling range than said gasoline fraction, mixing said distillate after passage through said adsorptive material and while heated, with a substantially large quantity of the heated heavier oil, vaporizing said gasoline fraction from the heavier oil in a vaporizing zone, leaving polymerized and sulphur-containing constituents of the distillate in the heavier oil, condensing the vaporized gasoline fraction, removing from said vaporizing zone and again mixing with the polymerized distillate a continuously circulated stream of said heavier oil, separating residual bodies from said circulated stream of heavier oil, and adding fresh oil thereto.

13. The process of treating heated cracked petroleum distillate containing a gasoline fraction, that includes subjecting the distillate to polymerization by contacting it with adsorptive material in a polymerizing zone, introducing the distillate from said polymerizing zone into an enlarged mixing zone, passing oil having a considerably higher boiling range than said gasoline fraction through a heating zone and discharging the heated oil into the mixing zone at a temperature higher than the temperature of the distillate being introduced thereto and above the vaporizing temperature of said gasoline fraction, flowing the distillate upwardly through the higher boiling oil and thereby causing polymerized and sulphur-containing bodies in the distillate to become retained in the higher boiling oil, removing the vaporized gasoline fraction from the higher boiling oil and subjecting the removed vapors to condensation, and separately removing the unvaporized higher boiling oil from said mixing zone.

WILLIAM T. HANCOCK.
